CLAIM

I claim the ornamental design for an electronic device panel, as shown and described.

DESCRIPTION

FIG. 1 is a front perspective view of an electronic device panel showing the first embodiment of my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view of a second embodiment of my design;

FIG. 9 is an enlarged view of the encircled portion in FIG. 1; and,

FIG. 10 is an enlarged view of the encircled portion in FIG. 8.

The broken lines in the figures show portions of the electronic device panel which form no part of the claimed design.

The dot-dash broken lines in the figures represent an unclaimed boundary line and form no part of the claimed design.

The dot-dot-dash broken lines encircling portions of the claimed design that are illustrated in enlargements form no part of the claimed design.
